UNITED STATES PATENT OFFICE.

HARRY A. FOOTHORAP, OF HARRISBURG, PENNSYLVANIA, ASSIGNOR TO ELLIOTT-FISHER COMPANY, OF NEW YORK, N. Y., A CORPORATION OF DELAWARE.

TOLL-SLIP PLATEN.

Application filed May 14, 1925. Serial No. 30,266.

This invention relates to flat platen typewriters and more particularly to what is known as a toll slip platen, especially adapted for the manipulation and printing of the toll slips or statements of telephone companies.

The object of the invention is to equip a flat platen typewriter with a small platen which may be manipulated with great speed 10 in the printing of toll slips.

The invention consists, generally, in providing, in lieu of the usual line space frame of a flat platen typewriter, a special support for both the typewriter carriage and a movable toll slip platen; the former being movable as usual for letter spacing and the platen being shiftable for line spacing by the manipulation of a line space key, and automatically movable to an unobstructed loading position upon the operation of a release key.

Another object of the invention is to equip a platen of this character with ordinary work holding means controlled by the position of the platen and designed to engage and securely hold the work as the platen is moved away from the loading position.

In the accompanying drawings:

Figure 1 is a plan view of the platen and carriage support with the carriage omitted and the platen shown in the loading position.

Figure 2 is a similar view with the platen pushed back to a writing position.

Figure 3 is a view similar to Figure 2, but showing the platen at its rearward limited movement.

Figure 4 is a transverse section on the line 4—4 of Figure 3.

Figure 5 is a view on an enlarged scale to show more clearly the action of the line space mechanism.

Figure 6 is a sectional elevation illustrating the operation of the line space mechanism.

Figure 7 is a detailed sectional view of the platen and the work clamp.

1 indicates the base or support formed with a platen guideway 2 extending from front 50 to back, and front and rear transverse guide rails 3 and 4 for the support of the usual traveling carriage 5 of a flat platen typewriter. The carriage indicated diagrammatically in Figure 2 is that of the well known Elliott-Fisher billing machine, which

in the present instance is connected by a tape 6 with a carriage propelling drum 7 of usual form which in the present structure is mounted at the end of the rear carriage guide 4.

Mounted to slide in the guideway 2 is a flat platen 8, a portion of which is provided with the usual rubber facing 9 upon which is intended to be imposed the toll bill or other work sheet 10. Disposed at the rear end of the effective or rubber covered portion of the platen is a top clamp 11. This clamp is carried by a hinge bar or pintle 12, mounted in bearing lugs 13 and secured by one or more spiral springs 14 which tend to urge the clamp 11 toward the platen. In other words the clamp 11 is a spring clamp and at the left hand end of its pintle 12 is a cam arm 15, which, when the platen approaches the forward or loading limit of its movement, is designed to ride upon a releasing cam 16 secured at the front edge of the support 1. Thus when the platen is in its forward or loading position the clamp 11 will have been automatically raised and the written toll slip thereby released to permit its removal and the reloading of the platen with a new slip. If, as is entirely possible, a number of toll slips are imposed on the platen and held by the clamp, the frequent reloading of the platen is unnecessary as the release of the clamp upon the forward movement of the platen will enable the operator to remove the top or written toll slip and immediately return the platen for the writing of the next slip.

Obviously, as the platen is moved back from the loading position shown in Figure 1, the cam arm 15 will be withdrawn from the cam 16 so that after slight movement 95 of the platen the clamp will be restored to its clamping position by its springs. The retraction of the platen to the loading position from any writing position is effected by a platen retracting spring 17 located below the support 1 and secured at one end thereto as indicated at 18. At its opposite end the spring is secured to a hook 19 formed at the end of an arm 20 extending from the lower end of a shaft 21, passed through the support 1 and provided at its upper end with a comparatively long platen retracting arm 22. The arm 22 is provided at its free end with a slot 23 through which is extended a pin 24 carried by the rear end 110

of the platen. The spring 17 exerts a constant tension, tending to urge the platen to its forward or loading position. During the writing range of movement of the platen, however, it is held against movement by a holding dog 25 which co-operates with a ratchet feed rack 26, secured to and extended along the right hand edge of the platen. The dog 25 is formed at one end of a platen release lever 27, fulcrumed at 28 on the support and having at its front end a release key 29 convenient to the hand of the operator. The release lever 27 is normally retained in its active or holding position by a spring 30, but by pressing the key 29 may be swung to release the platen by withdrawing the holding dog 25 and thus permit a retraction of the platen to the loading position under the impulse of the spring 17. When the platen has been pushed back after reloading, to the first writing position, as shown in Figure 2, it will be held as stated, by the holding dog 25. During the subsequent operation of the machine the platen may be pushed back by the operator one line space at a time, this operation being accompanied by the clicking of the dog 25 over the teeth of the rack. It is contemplated to perform this line space operation by means of line space mechanism including a line space key 31 carried at the front end of a line space lever 32, located adjacent to one end of a line space yoke 33 urged in one direction by a spring 34, and extended across the support 1 in rear of the carriage guide 4.

The yoke 33 is provided, as shown in Figure 6, with a depending arm 35, adapted to engage a projection 36 on a lever 37, fulcrumed at one end on the support 1 and connected by a draw rod 38 with a pivoted pawl carrier 39 equipped with a retracting spring 40 and with a stop arm 41 that contacts with the support and limits the retractile movement of the carriage. Pivoted at the end of the carrier 34 is a feed pawl 42, co-acting with the feed rack 26 and having a tail piece 43 in cooperative relation with a fixed pin 44. Tending constantly to urge the feed pawl toward the rack is a spring 45 secured to the tail piece 43 near the pin 44, which in the normal position of the platen feed mechanism holds the feed dog in its disengaged position as shown in Figure 5.

Assuming that a line has been written and that it is desired to feed the platen rearward one line space, the line space key 31 is depressed thus rocking the yoke 33 and causing the arm 35 to move rearwardly. The engagement of the arm 35 with the lever 37 will swing the latter and with it the carrier 39. This movement of the parts as shown in Figure 5 from the full to the dotted line position, will permit the feed dog 42 to first move into engagement with the rack and then advance the rack and platen until the

carrier 39 is arrested by a stop pin 46. Upon the release of the key 31 the parts will be retracted by the springs 34, 40 and 45, to their normal position, but it will be obvious that a retraction of the platen from its new position will be prevented by the holding dog 25 which clicks over the teeth of the feed rack as the platen is fed and is always in position to hold the platen when the latter is released by the withdrawal of the feed dog. The retraction of the line space key and its associated parts is limited by a stop 47 extended from the rear carriage guide and engaged by the arm 35.

It will appear from what has been said, that in operation a toll slip is placed on the platen occupying the position shown in Figure 1, after which the platen is moved back, the first position of this movement serving to drop the clamp 11 automatically to hold the work and further backward movement serving to present the toll slip under the printing point of the typewriter and to bring the feed rack into engagement with the holding dog. As the writing progresses the line space feed of the platen is effected by manipulating the line space key and when the operation has been completed the pressing of the release key 29 results in the release of the platen and permits it to shoot forward to the loading position under the impulse of the platen retracting spring to automatically render the platen accessible and to automatically release the work supported thereon.

It is thought that from the foregoing the construction, operation and advantages of my present invention will be clearly understood, but I reserve the right to effect such changes and modifications of the illustrated structure as may fall within the scope of the protection prayed.

What I claim is:

1. In a machine of the class described, the combination with a support having transverse carriage guides and a platen guideway disposed in right angular relation, of a platen movable in the guideway, a platen retracting arm carried by the support and connected to the platen, a spring for moving the arm, a platen line spacing mechanism and platen holding and releasing mechanism including a release key located in front of the support.

2. The combination with a support, having carriage guides and a platen guideway disposed in right angular relation, of a rock shaft extended through the support, an arm extended from the rock shaft, a platen movable in the guideway and having slot and pin connection with the arm, a spring tending to urge the arm in one direction and platen feeding and holding mechanism.

3. The combination with a support, having carriage guides and a platen guide-

way disposed in right angular relation, of a platen movable in the guideway, a rock shaft extending vertically through the support and having arms located above and below the support, a platen retracting spring connected to one of the arms, a connection between the other arm and the platen, and platen feeding and holding mechanism.

4. The combination with a support, having carriage guides and a platen guideway disposed in right angular relation, of a platen movable in the guideway, platen retracting means and platen feeding means, said feeding means including a key operated yoke disposed parallel with the carriage guides, an arm extended from said yoke, a pawl carrier operated by said arm, a feed pawl movable with the pawl carrier

and a rack fixed to the platen and engaged by the feed pawl.

5. In a machine of the class described, the combination with a support, having carriage guides and a platen guideway disposed in right angular relation, of a platen movable in the guideway, platen retracting means, a pawl carrier located beyond one side of the platen and equipped with a feed pawl, a rack fixed to the platen to be engaged by the pawl, a lever located adjacent to the rear of the support and connected to the pawl carrier to swing the same, a line space key and an arm operated by the line space key to swing the lever last named.

In testimony whereof I hereunto affix my signature.

HARRY A. Foothorap.
